COMBINATION SWIMMING POOL, SKATING RINK AND EXHIBITION FLOOR

Ralph N. Skrainka, Ladue, Mo.

Application May 27, 1953, Serial No. 357,829

3 Claims. (Cl. 272—3)

The present invention relates generally to masonry and concrete structures, and, more particularly, to a structure the activities area of which can be used alternately as a swimming pool, a skating rink, or an exhibition floor, and which contains tiers of seats overlooking the activities area.

It is a well known fact that a large percentage of the population in the United States is very much interested in athletic events, both as participants and spectators, and, because the usual practice in most cities is to have only one large athletic event at a time, it is very advantageous to have a structure the activities area of which can be used alternately as a swimming pool, a skating ring, or an exhibition floor.

There are some structures in use at the present time which can be used either as a swimming pool or an exhibition floor, and others which can be used either as a skating rink or an exhibition floor, but none can be used as either a swimming pool, a skating ring or an exhibition floor.

It is an object of the present invention, therefore, to provide a novel structure containing an activities area which can be used alternately as a swimming pool, a skating rink, or an exhibition floor.

Another object is to provide a novel structure containing an activities area which can be used alternately as a swimming pool, a skating rink, or an exhibition floor, and which contains seats overlooking the activities area.

Another object is to provide a novel structure having an activities area, the central portion of which has a substantially level floor and which can be separated from the remaining portions by barriers so that it can be used either as a skating rink or an exhibition floor.

Another object is to provide a novel structure having an activities area in the form of a waterproof enclosure, the central portion of which is of uniform depth, the end portions of which are of increasing and decreasing depth, respectively; whereby the structure can be used either as a swimming pool when filled with water; as an exhibition floor by removing water and erecting barriers at the ends of the central portion; or as a skating rink by erecting barriers, flooding the central portion with a thin layer of water, and then freezing the same.

Further objects and advantages of the present invention will be apparent from the following description, reference being had to the accompanying drawings wherein a preferred embodiment of the present invention is shown, in which:

Fig. 1 is a top plan view of a structure embodying the teachings of the present invention;

Fig. 2 is a vertical longitudinal sectional view of the structure;

Fig. 3 is an enlarged vertical transverse sectional view taken on the line 3—3 in Fig. 1;

Fig. 4 is a perspective view of the structure showing the activities area prepared for use as a swimming pool; and

Fig. 5 is a perspective view of the structure showing

2

the activities area prepared for use as an exhibition floor for the playing of tennis matches.

Referring to the drawings more particularly by reference numerals, 10 indicates generally a structure made of reinforced concrete or the like and embodying the teachings of the present invention. It includes an activities area 12 which has seating areas 14 on both sides thereof.

The activities area 12 is recessed and includes side walls 16 and 18, curved end walls 20 and 22, and floor segments 21, 23 and 25. For purposes of description, the activities area will be considered as being divided into a central section 24, a deep end section 26, and a shallow end section 28. The central section 24 is roughly rectangular in shape and the end sections 26 and 28 are roughly semicircular in shape. The floor segment 23 of the central section 24 may be covered with asphalt, macadam or the like, or may be finished with cement in the conventional manner.

20 As shown in Fig. 2, the floor segment 23 of the central section 24 is substantially level, whereas, the floor segment 21 of the deep end section 26 slopes downwardly away from the central section and then upwardly to the end wall 20. A vertical, transversely extending wall 30 25 separates the central section 24 from the shallow end section 28, the floor segment 25 of the latter being sloped upwardly from the top of the wall 30 toward the end wall 22.

A series of spaced openings 32 are contained in the 30 floor between the segments 21 and 23, and, hence, between the deep end section 26 and the central section 24, and a series of similar openings 34 are contained in the top of the wall 30, both of said series of openings extending from one side wall to the other as shown in Fig. 1, 35 for a purpose to be described hereinafter.

The floor segment 23 of the central section 24 contains markings 36 for a tennis court or the like (Figs. 1 and 5), and openings 38 to accommodate the end posts and guide wires for a tennis net 40 (Fig. 5).

40 A flat concrete apron 42 extends around the periphery of the activities area 12 and diving boards 44 are mounted on it adjacent the deep end section 26. Short ladders 46 extend from the inner edge of the apron 42 down into the activities area 12 as shown in Figs. 1 and 2. An overflow trough 48 (Fig. 3) extends around the activities area 12 at the upper edge of the side and end walls, and resilient members 50 (Fig. 3) are embedded at the lower inner surface of the side walls 16 and 18 and the transverse wall 30 for a purpose to be described hereinafter. A drain 53 is contained in the bottom wall of the deep end section 26.

55 Removable barriers 56 and 58 (Fig. 5), which contain supporting means for holding engagement with the openings 32 and 34, respectively, are provided to be erected at the ends of the central section 24, as will be more fully described hereinafter.

The tiered seating areas 14 are shown diagrammatically, and it is to be understood that they may be provided with seats of any conventional design, and that entrances (not shown) may be located at either the ends or at the rear of the seating areas 14. Manifestly, locker rooms, showers, etc. (not shown), may be constructed under the seating areas 14.

60 To use the structure as a swimming pool, as shown in Fig. 4, guard ropes 54 are installed between the deep end section 26 and the central section 24, and the central section 24 and the shallow end section 28, and the activities area 12 filled with water.

65 To use the structure as an exhibition floor as, for example, for playing tennis matches (Fig. 5), the water and the guard ropes 54 are removed, the net 40 placed in

3

position, and the barriers 56 and 58 erected over the openings 32 and 34, respectively.

It is to be understood that the central section can also be used for basket ball games, and the like, by removing the net 40, installing a removable wood flooring (not shown), and using removable type basket supports (also not shown).

Also, it is manifest that it can be used for prize fights, wrestling matches, and the like, by erecting a removable "ring" in the center of the central section and installing 10 temporary seats around it.

To use the structure as a skating rink (Fig. 3), the barriers 56 and 58 are erected, the floor of the central section cleared, refrigeration pipes 60 laid thereon, the central section flooded with a relatively thin layer of 15 water, and the latter frozen by pumping refrigerant through the pipes 60. The lower portion of the barrier 56 is substantially waterproof and the lower edge thereof forms a substantially water tight seal with the bottom wall of the central section 24 so that practically no water escapes from the central section during the ice forming period. Any water which might escape merely flows into the deep end section and into the drain 53. The resilient members 50 permit the ice to expand when forming without injuring the side walls 16, 18 and 30.

Thus, it is apparent that there has been provided a novel structure which fulfills all the objects sought therefor.

It is to be understood that the foregoing description and the accompanying drawings have been given only by way of illustration and example, and that changes and alterations in the present disclosure, which will be readily apparent to one skilled in the art, are contemplated as within the scope of the present invention which is limited only by the claims which follow.

What is claimed is:

1. A structure which can be used as a swimming pool, skating rink or exhibition floor; comprising an elongated waterproof enclosure having a side wall and a bottom wall, the central portion of said enclosure being of roughly 40 rectangular shape, and the end portions of roughly semi-

circular shape, the upper surface of the bottom wall of the central portion being substantially level, the bottom wall of one end section sloping downwardly away from the central portion, and the bottom wall of the other end section sloping upwardly away from the central portion, 5 said level surface containing markings for a tennis court or the like; means for supporting the posts for a tennis net or the like; removable for isolating the latter from the end portions; barriers at the ends of the central portion; and seats overlooking the enclosure.

2. An arena for a variety of specialized athletic contests and exhibitions, said arena comprising an elongated activities area circumvented by a continuous wall, a floor for said activities area, said floor being below the upper level of said wall, said floor including an intermediate portion having a substantially flat horizontal surface and end portions having surfaces at levels respectively above and below the level of said flat horizontal surface, and a waterproof barrier wall removably disposed at the junction of the intermediate floor portion and the end floor portion having its surface below the level of the intermediate portion, said barrier wall being adapted to cooperate with the aforementioned continuous wall in retaining water upon said intermediate floor portion.

3. The arena of claim 2 wherein those portions of the continuous wall which adjoin the intermediate floor portion are provided with resilient members adapted to yield in response to exertion of lateral pressure thereagainst as a result of the freezing of water retained upon the floor portion.
